TREATING HYDROCARBON OIL

Robert E. Manley, Port Arthur Tex., assignor to
The Texas Company, New York, N. Y., a cor-
poration of Delaware

Application June 27, 1930, Serial No. 464,331

6 Claims. (Cl. 196—18)

This invention relates to improvements in treating paraffine wax containing hydrocarbon oil, more particularly distillate oils, in the lubricating oil range to remove the paraffine wax, the presence of which in the final oil is undesirable; the invention also relates to the removal of those wax constituents remaining in the oil after dewaxing by any of the prior art methods.

Treating hydrocarbon oil to remove the paraffine constituents therefrom is known in the industry as dewaxing the oil. Among the several methods of dewaxing hydrocarbon oil which are practiced is that of mixing the oil to be treated with a less viscous solvent oil, such as naphtha, chilling the mixture to crystallize or precipitate the waxy constituents and then centrifuging the chilled mixture to separate the wax from the mixture of oil and solvent.

While this is a widely practiced and economical mode of operation, it does have certain limitations outside of which the operation of the process becomes uneconomical. For example, after the wax containing oil is mixed with a solvent, or as it is commonly called cut-back, the mixture or cut-back stock is chilled to —10 or —20° F. at which temperatures the waxy constituents will tend to precipitate, and it is then delivered to a centrifuge machine where the separation of the wax from the oil is accomplished. Even though the cut-back stock is moved only a short distance from the chiller through insulated channels to the centrifuge, it is impossible to prevent it from heating up somewhat and consequently it may be centrifuged at approximately 0° F. when it has been chilled to the previously mentioned temperature which is considered to be within the economical limits of this type of operation.

The characteristics of the paraffine to be removed from the oil may be such that all of it does not precipitate or collect in removable or separable form at this temperature, or it may be that the step of separation is not fully effective or for some other reason that a portion of the paraffine may be thrown back into solution with the oil. Accordingly, when treating oil by the centrifuge method to remove the paraffine constituents and operating within economical limits a small portion of the paraffine will remain in the oil. This is extremely objectionable because a rise in the pour test of the oil occurs upon only the slightest increase of the paraffine content. It is also objectionable because an otherwise highly treated oil containing more than a trace of paraffine will become cloudy, that is, it will lose its

transparency and luster at normal low atmospheric temperature.

It is to be understood that oil dewaxed by the centrifuge method is not necessarily the only dewaxed oil which may contain a small amount of paraffine, but an oil which has been dewaxed by other processes may also contain a small amount of paraffine.

Accordingly, the present invention is a very useful and valuable adjunct to any dewaxing process and it has for its chief object the removal of such paraffine as remains after the primary dewaxing step is finished.

A clear understanding of the details of the invention may be had by referring to the following description and the accompanying drawing illustrating in diagrammatic elevation a preferred embodiment of apparatus suitable for practicing the process, and which apparatus, for the most part, is substantially similar to that described in my U. S. Patent No. 1,825,324.

The oil to be dewaxed, for example, a wax-bearing cylinder stock fraction, is introduced from a tank 1 into a mixing tank 2 wherein it is thoroughly mixed with a solvent such as petroleum naphtha, and delivered from a tank 3. The proportion of wax-bearing oil to solvent may vary, for example, from 30% to about 70% by volume of the solvent. The diluted oil is then forced by a pump 4 through a chiller 5, wherein the temperature is reduced sufficiently to effect precipitation of solid and semi-solid wax constituents contained therein.

The chilled mixture containing precipitated wax is then delivered to a centrifuge 6 to effect separation between the wax constituents and the oil. The wax constituents are removed from the centrifuge in the form of petrodatum which is drawn off through a pipe 7 to a receiving tank 8 for further treatment, as may be desired.

The liquid hydrocarbons from which the petrodatum has been separated are drawn off from the centrifuge through a line 9 to a receiving tank 10. During passage through the centrifuge, the temperature of the oil may have been raised appreciably and recooling may, therefore, be necessary or desirable, or cooling to a still lower temperature, for that matter, prior to subjecting the oil to the subsequent filtration step for the removal of remaining wax. The oil mixture is, therefore, delivered from the tank 10 by a pump 11 and conducted through a chiller 12 wherein it is subjected to such further cooling as may be desired.

The cooled mixture is then delivered to a mixer 55

13 wherein filter-aid material, such as diatomaceous earth, is admixed with the oil. The filter-aid material is delivered to the mixer from a tank 14, either in the form of a dry powder or 5 in the form of a slurry, formed by mixing the filter-aid material with naphtha or other solvent. The mixer 13 is provided with suitable mixing or stirring means in order to effect thorough mixing of the filter-aid material with the oil.

10 After the addition of the filter-aid, the mixture may, if desired, be subjected to additional cooling by circulating the contents of the mixer 13, or a portion thereof, through a separate chilling coil 15.

15 The cold mixture of suspended wax and filter-aid material is drawn off from the mixer 13 by a pump 16 and delivered to a filter 17 advantageously of the pressure type.

20 The oil passes through the filter and is discharged therefrom through a pipe 18 into a receiving tank 19. The dewaxed oil collecting in this tank may then be drawn off for the purpose of recovering the solvent therefrom.

25 At the end of the filtering cycle, the contents of the filter are displaced by means of gas introduced to the filter shell through a cooling coil 20 and pipe 21. The gaseous displacing media may be an inert gas, such as flue gas. Following this displacing step, the filter cake of wax and filter-aid 30 material may be subjected to washing with fresh solvent liquid delivered to the filter by a pump 22 from a tank 23. This washing solvent is passed through the filter cake and discharged from the filter through a pipe 24 into a receiving tank 25. 35 This washed solution may be used for subsequent washings until the concentration of the dissolved oil has reached the point where it is desirable to subject the solution to evaporation to recover the solvent and separate the oil.

40 After washing, the filter cake may be dried by forcing cold gas therethrough from the cooler 20 previously referred to. The filter cake is discharged from the filter shell into a receiver 26 where it may be treated with warm solvent or 45 by other means for the separation of wax from the diatomaceous earth, after which the earth may be returned to the vessel 14 and used again for dewaxing further stock.

45 In practicing the improved step, the dewaxed oil is delivered from the centrifuge 6 or other dewaxer while still cool, through the chiller 12, which further reduces the temperature of the oil only slightly, into a mixer 13, where a small amount of filter-aid material, say only three or four pounds per barrel of oil is added and the oil and the filter-aid thoroughly mixed therein. The mixture is then withdrawn from the mixer 13 and passed through the filter 17 from which the filtrate or paraffine free oil is withdrawn, while 50 the filter-aid material and the paraffine constituents being removed collect in the interior of the filter and are ultimately removed. The magnitude of the entire equipment, that is, the chiller, the mixer and the filter, depends, of course, upon the 55 desirable rate of movement of the oil therethrough and as the improved process is capable of being operated at high relative rates, the partially dewaxed oil from a number of centrifuges or several filters may be run through a single unit of relatively small size in the practice 60 of this process. In some instances it may be of advantage to add the filter-aid to the partially dewaxed oil and to then chill the mixture rather than chill the oil and then add the filter-aid as described above.

5 Another manner of practicing the improved process is to slightly further chill the partially dewaxed oil and then pass it through a filter, the leaves or filtering surfaces of which have been previously coated with a suitable filter-aid material to form a porous coat or cake thereon previous to oil but impervious to waxy material.

10 Still another manner of practicing the improved process is to slightly further chill the partially dewaxed oil and simultaneously chill a 15 previously prepared pumpable or otherwise movable fluent slurry of filter-aid material and naphtha or other solvent, mix the chilled oil and the chilled slurry and filter this mixture. This procedure offers a particular advantage in that by chilling the filter-aid material as well as the wax containing oil before mixing the temperature of the chilled oil is not raised as it would be if filter-aid at atmospheric temperature was 20 added.

25 The process of the present invention is capable of being practiced successfully in a number of ways and it is not intended that its spirit and scope be limited by the descriptive terms employed, but rather by the appended claims.

What I claim is:

1. The process of dewaxing hydrocarbon lubricating oil to yield an oil of low pour test and free from cloudiness due to precipitated wax at temperatures substantially above the temperature at 30 which the oil will pour, which comprises chilling the oil to a temperature at which precipitation of the wax constituents occurs, separating the bulk of the precipitated wax from the oil in the absence of a solid, inert material such as diatomaceous earth, then subjecting the chilled partially dewaxed oil to filtration in the presence of a filter-aid material such as diatomaceous earth at a temperature substantially the same as the 35 temperature at which the oil was partially dewaxed whereby the comparatively small quantity of wax remaining in the oil is removed.

2. The process of dewaxing hydrocarbon lubricating oil to yield an oil of low pour test and free from cloudiness due to precipitated wax at 45 temperatures substantially above the temperature at which the oil will pour, which comprises chilling the oil to a temperature at which precipitation of the wax constituents occurs, separating the bulk of the precipitated wax from the oil by difference in specific gravity and in the absence of a solid, inert material such as diatomaceous earth, then subjecting the chilled partially dewaxed oil to filtration in the presence of a filter-aid material such as diatomaceous 50 earth at a temperature substantially the same as the temperature at which the oil was partially dewaxed whereby the comparatively small quantity of wax remaining in the oil is removed.

3. The process of dewaxing hydrocarbon lubricating oil by a method involving centrifuging, to yield an oil of low pour test and free from cloudiness due to precipitated wax at temperatures substantially above the temperature at which the oil will pour, which comprises chilling the oil to a 55 temperature at which precipitation of the wax constituents occurs, centrifuging the chilled oil whereby the bulk of the wax constituents are separated from the oil, then subjecting the chilled partially dewaxed oil to filtration in the presence of a filter-aid material, whereby the comparatively small quantity of wax remaining in the oil after centrifuging is removed.

4. The process of dewaxing hydrocarbon lubricating oil by a method involving centrifuging, to 60

yield an oil of low pour test and free from cloudiness due to precipitated wax at temperatures at which the oil will pour, which comprises chilling the oil to a temperature at which precipitation of the wax constituents occurs, centrifuging the chilled oil whereby the bulk of the wax constituents are separated from the oil, then subjecting the chilled partially dewaxed oil to filtration in the presence of a filter-aid material at a temperature substantially the same as the temperature at which the oil was centrifuged, whereby the comparatively small quantity of wax remaining in the oil after centrifuging is removed.

5. The process of dewaxing hydrocarbon lubricating oil by a method involving centrifuging, to yield an oil of low pour test and free from cloudiness due to precipitated wax at temperatures substantially above the temperature at which the oil will pour, which comprises chilling the oil to a temperature at which precipitation of the wax constituents occurs, centrifuging the chilled oil

whereby the bulk of the wax constituents are separated from the oil, subjecting the chilled partially-dewaxed oil to filtration in the presence of a filter-aid material, whereby the comparatively small quantity of wax remaining in the oil after centrifuging is removed.

6. In the dewaxing of mineral lubricating oil containing wax, including a small amount of wax responsible for cloudiness in the oil and which is not removed with the bulk of the wax by centrifuging, wherein the oil is mixed with a solvent, chilled to precipitate wax, and the precipitated wax removed therefrom, the method of removing the wax comprising subjecting the oil to both centrifuging to remove the bulk of the wax constituents and filtering in the presence of a filter-aid material to remove cloud-forming wax, thereby yielding lubricating oil of low pour test and free from cloudiness due to precipitated wax at temperatures at which the oil will pour.
